DOOR CLAMPING DEVICE

Due to the present day trend toward the use of enamel finish for stoves, kitchen cabinets, heaters and the like, much damage to enameled parts occurs when the enameled door panels become loosened in transit.

The principal object of the present invention is to reduce breakage and other damage to a minimum by providing inexpensive clamping means for securely holding the door panels in place against the conventional front frame during shipment.

Another object of the invention is to provide a door panel clamp which can be readily applied and as easily removed from the front frame of a stove or the like.

A still further object of the invention is to provide a door panel securing device which does not mar a stove or the like when applied thereto and which does not leave the stove in an unsightly state when the device is removed.

Other objects and advantages of the invention will be apparent from the following description considered with the accompanying drawing, in which:

Figure 1 is a front view of a stove or range having a plurality of the improved clamping devices applied thereto:

Figure 2 is a fragmentary section through the front frame of a stove and adjacent portions of a pair of doors or closure members, showing the clamping member in place.

Referring more particularly to the drawing in which like numerals designate like parts throughout the several views, 5 designates the front frame of a stove or range 6. In the present instance the range comprises baking and broiling oven compartments 7 and 8 at one side thereof and at the opposite side a burner compartment 9 and upper and lower utility compartments 10 and 11 respectively. The front frame 5 preferably but not necessarily of integral angle iron construction comprises vertical members 12 and horizontal members 13 which provide the customary rectangular openings through which access may be had to the several compartments 7 to 11 inclusive. Conventional doors or drawers 15 each comprising front and rear sheet metal panel members 16 and 16', normally close the several rectangular door or drawer openings. According to common practice the front panel members 16 are faced with enamel. As previously stated one of the biggest causes of damage to enameled parts, such as the front door panels is the difficulty of securely fastening the door panels so that they will not be loosened in transit. This

trouble is obviated or minimized by the use of my improved clamping device [7].

It should be noted here that in conventional stove constructions the adjacent edges of the compartment doors or drawers 15 are slightly spaced from each other, as at 18. According to the present invention the front frame 5 is formed with one or more tapped holes 19, preferably located at a point equidistant from the adjacent corners of two or more doors 15 and registering with the openings or spaces 18, between adjacent doors.

The clamps 17 comprise small headed screws or bolts 20 adapted to be threadedly received in the tapped holes 19, each screw being provided with a spacer sleeve 21 of heavy paper and of such length that its outer end will be flush with the outer face of frame panel members 16 when the inner end of the sleeve bears against the front frame 5. Arranged in superimposed relation between the head of the screw 20 and the outer end of the spacer sleeve 21, in the order named, is a preferably two-ply corrugated paper panel engaging strip 22, a large metal washer 23 and a small metal washer 24. When the screw 20 is forced inwardly by means of a screw-driver or other suitable hand tool the relatively large heavy flexible paper strip 22 is forced tightly against the corner faces of the respective door panels thus clamping the panels tightly to the front frame. The strip 22 is preferably rectangular in shape for economy of manufacture, but it will be obvious that the same may be of circular or any other desired shape, provided only that the strip is of such size that the marginal edges thereof are adapted to overlap the adjacent front faces of the adjacent door corners. Due to the flexible compressible nature of the corrugated paper strips 22 the clamping screws can be screwed up without danger of injuring the porcelain panels. Furthermore it will be seen that the slightly compressible nature of the spacing sleeve 21 causes the latter to serve as bolt or screw lock when the inner and outer ends of the sleeve are respectively forced against the frame and the corrugated inner face of the paper strip 22.

In a stove having six compartments such as shown in the drawing, two tapped holes 19 will be provided and of course two clamping devices 17 will be sufficient to securely hold the six door panels in place during shipment. The screws 20 and associated parts of the clamps 17 are removed when the stove reaches its destination and because of the small cost involved these parts

will be discarded. Due to the narrowness and relative depth of the space 18 between the door panels, the tapped holes 19 are not visible when the screws are removed.

Having thus described my invention what I claim is:

A clamp for securely holding a plurality of spaced enameled door panels to the front frame of a stove in transit comprising a headed screw adapted to engage in a tapped opening formed in the front frame in register with the space between the door panels, a substantially square flexible strip of readily compressible corrugated paper carried by said screw and adapted to over-

lap and engage one or more of said door panels and force the same tightly to said frame when said screw is screwed home, a metal washer on said screw between said screw head and said flexible strip, and a relatively heavy compressible paper tube loosely encircling said screw, said tube being of a length such that when the inner end thereof is seated against said frame the outer end of the tube will be substantially flush with the outer faces of the said panels and in position to be engaged and compressed by said flexible strip to lock the screw against accidental rotation when said screw is screwed home.
